UNITED STATES PATENT OFFICE

JOHN H. KOLTS, OF CRAFTON, AND EDWARD A. KRAH, JR., OF PITTSBURGH, PENNSYLVANIA, ASSIGNEES TO PITTSBURG WATER HEATER COMPANY, OF PITTSBURGH, PENNSYLVANIA, A CORPORATION OF NEW JERSEY

GAS BURNER

Application filed July 22, 1927. Serial No. 207,617.

This invention relates to burners such as are used for the burning of either natural or artificial gases and the burner of the present invention has been developed in connection with and is particularly adapted for use in hot water heaters. It will therefore be described in the preferred form it has taken in connection with such use although we wish it to be understood that the invention is not necessarily limited to this class of service.

The invention is particularly adapted for incorporation in what is known as a rose type burner, i. e., a burner in which the outlet orifices are arranged in a somewhat extended horizontal plane. For instance a flat burner with a series of outlet orifices arranged in a circle would be known as a rose burner. However, there have been many different arrangements of the outlet orifices in rose burners and in the present instance we have disclosed an arrangement or disposition of the outlet orifices which has proven to be exceptionally satisfactory and which will be described in detail hereinafter.

The particular objects of our invention include the provision of a burner of the character described in which it is unnecessary to use a gauze to prevent back-firing; to provide a burner which will produce no carbon monoxide; to produce a burner which will clear itself of flame should ignition take place at the outlet spud in the base of the Bunsen tube.

It is a further object of the invention to provide a burner having its outlet orifices and secondary air passages so arranged as to provide secondary air at the side of every outlet orifice as well as to arrange for the entrainment of the secondary air with as little resistance as possible and in connection with these two objects we provide sloping upper faces for the burner, upon which there will be little or no tendency for dirt to accumulate.

Our improvements enable us to make the burner a one-piece casting which permits us to provide a considerably lighter and cheaper construction. In a general way, therefore, we aim to provide a burner which can be more

easily and cheaply manufactured, one which will be cooler in service yet one which has increased efficiency with a small flame of high temperature, also a burner in which the rate of consumption is increased, and combustion more nearly complete with the elimination of carbon monoxide. In fact our improved burner approaches more closely than any other burner with which we are familiar the type of burner known as the blast burner wherein the flame is of the highest temperature.

The accompanying drawings are made to scale although slightly smaller than the average size burner.

Fig. 1 is a plan view of the burner;
 Fig. 2 is a section on the line 2—2 of Fig. 1;
 Fig. 3 is a section on the line 3—3 of Fig. 1;
 Fig. 4 is a section on the line 4—4 of Fig. 1;
 Fig. 5 is a section on the line 5—5 of Fig. 1;

and

Fig. 6 is a section on the line 6—6 of Fig. 2.
 The burner casting comprises a head portion A and a Bunsen mixing tube B. In the head there is a hub or central distributing chamber 1 having a substantially flat horizontal upper surface 2 from which radiate a plurality of gas distributing channels 3. The upper face of each radiating channel is formed with a ridge or rib 4 so as to provide downwardly sloping top surfaces or faces 5.

The outer ends of the radiating channels are connected by means of a similarly ridged peripheral channel 6. In the structure illustrated the peripheral channel 6 is broken at the point 7 for the purpose of providing a space into which a pilot light can extend. This provision, however, is not necessary to the invention as other types of pilot lights may be used which do not necessitate an opening in the peripheral channel 6 in which event the channel 6 can be a complete circle.

We have provided outlet orifices in the radiating channels 3 as well as in the peripheral channel 6 and these orifices take the shape of a series of upstanding outlet spuds 8 having, preferably, small drill holes 9 (say from #44 to #52 gauge). These spuds we prefer to arrange so that they extend upon the average about 7/64 to 1/8 inch above the top of the

ridge 4 although different types might be used so long as the openings and the rest of the burner parts were properly proportioned thereto.

The Bunsen mixing tube B is of especial design and construction and involves the use of a Venturi tube 10 as shown most clearly in Fig. 2. The outlet 11 of the venturi is arranged to discharge upwardly in substantially the center of the burner head so that the stream of mixed gas and air will impinge upon the under surface of the flat face 2 from whence it is deflected outwardly to each of the channels 3 in substantially equal amounts. The channels 3 are arranged to taper or become smaller as they approach the peripheral chamber or channel 6. By these means we are enabled to maintain a substantially equal pressure of gas in all parts of the burner head from which outlet spuds are fed.

The throat 12 of the Bunsen mixer is so proportioned with respect to the total area of the outlet spud openings 9 as to enable the mixture to rush out at greater speed and volume than that at which they enter. After the mixture passes the throat 12, the venturi, of course, acts to gradually increase the velocity and the outlet spuds are so proportioned to the rate of flow thru the Venturi tube as to prevent detrimental retardation of the increased rate of flow. We believe that this plays an important part in the ability of the burner to clear itself of flame should it become ignited at the inlet spud at the base of the bunsen.

The burner head may be provided with whatever supporting legs 13 may be necessary.

The enlarged base 14 is provided with the usual transverse web 15 having the outwardly projecting annular collar 16. Upon this shoulder 16 is mounted the usual air shutter 17 adjustable by rotation upon the collar 16.

In our improved construction the collar 16 is internally threaded as clearly shown in Fig. 2 and into these threads is screwed the member 18 which acts as a lock nut for the air shutter 17 as well as a guide and lock for the needle valve 19.

The housing 20 for the needle valve is slid into the interior of the member 18 (see Fig. 2) and after the parts have been properly positioned, the set screws 21 are screwed down into place.

The stem of the needle valve is supported at its forward end by means of the guide 22 which extends in from the inner wall of the housing 20. The outer end of the stem of the needle valve is carried in the bushing 23 and is suitably packed as at 24, the needle valve being adjustable by virtue of the fact that it is threaded at 25 into the interior of the bushing 23. By removing the cap member 26 the needle valve may be adjusted upon turning the knurled nut 27.

The housing member 20 has a lateral pro-

jection 28 to which the gas supply pipe 29 is coupled.

The point at which the gas enters the Bunsen mixer is, of course, known as the inlet spud and with our improved burner it is important that this spud does not extend too far into the bell 30 at the base of the Bunsen mixer. We have found that the proportions indicated in the drawings (see especially Fig. 2) will give substantially the best results.

Inasmuch as the amount of primary air entrained is of considerable importance in the successful operation of our improved burner, the peculiar locking arrangement which we have illustrated is particularly advantageous. It will be noted that the member 18 acts not only to lock the outlet spud in its proper position but also the air shutter. Furthermore it provides a guide for the inner end of the needle valve housing.

As will be seen upon inspection of the drawings, the burner can be made as a single piece casting which greatly lightens and cheapens the construction. No gauze is necessary to prevent back flash and the burner will function without the production of carbon monoxide. Furthermore as already pointed out the burner will clear itself of flame should it be ignited at the inlet spud at the base of the bunsen. It is an economical burner to use because it makes possible very complete combustion and the production of a very hot flame. It gives rise to less troubles from soot or the accumulation of other dirt, the sloping faces 5 on the burner head acting to discharge any particles of foreign matter which may fall upon them.

It will be noted that secondary air can be drawn up and past each series or row of outlet spuds 8. In other words all outlet spuds are directly flanged by a secondary air passage. There are no spuds which are not immediately adjacent to a secondary air opening. Furthermore the tapering or sloping faces 5 make possible the entrainment of the secondary air with the least possible resistance. All of these features cooperate to produce the improvements specified.

In conclusion it is desired to point out that we have so far not been able to determine from an exact scientific standpoint just the reasons why our improved burner makes possible the marked advantages above described. We would like to say, however, that a burner constructed substantially as shown and described will function as specified although we do not mean to say that the proportions and shapes of the various parts of the burner may not be altered and still obtain our improved results. We believe that the advantages to which attention has been particularly directed are in a large measure incident to the use of a Venturi mixing tube which is arranged to discharge at substantially the center of the distributing channels into a central

or hub chamber which has an imperforate upper face. In this way we are enabled to deliver the gas at substantially equal pressures at each and every outlet spud. Furthermore there is no detrimental retardation of the increase in flow incident to the use of the venturi because we have so proportioned the length and diameter of the outlet spuds to the length and diameter of the venturi as to enable the discharge of the gas to take place freely and quickly so as not to lose the benefit of the increase in speed. This, we believe, has a direct relation to the ability of the burner to clear itself of flame if ignited at the inlet spud as well as to the ability of the burner to function without danger of back-firing or back-flashing, as it is known in the art.

We claim:—

1. A gas burner comprising in combination, a hub chamber with an imperforate face, a plurality of channels radiating therefrom, and a Venturi mixer discharging thru the bottom of the hub chamber against said imperforate face.

2. A gas burner comprising in combination, a central or hub chamber with an imperforate face, a plurality of channels radiating therefrom, a peripheral channel connecting the outer ends of the radiating channels, and a Venturi bunsen discharging upwardly thru the bottom of the hub chamber toward the imperforate face.

3. A gas burner comprising a burner head with top and bottom walls, upstanding outlet spuds in the top wall arranged outwardly from a central imperforate hub, and a Venturi bunsen with its discharge opening in the bottom wall below said hub.

4. A gas burner comprising in combination a plurality of discharge channels, outlet orifices in the channels, a distribution chamber with an imperforate face from which said channels are supplied, and a Venturi bunsen delivering into the distribution chamber.

5. A gas burner comprising in combination, a central or hub chamber with an imperforate face, a plurality of channels radiating therefrom with upper faces longitudinally ridged, upstanding outlet spuds on the sides of the ridges, secondary air passages adjacent ridge sides, and a Venturi bunsen discharging upwardly thru the bottom of the hub chamber toward said imperforate face.

6. A gas burner comprising in combination, a central or hub chamber with an imperforate face, a plurality of channels radiating therefrom with upper faces longitudinally ridged, a similarly ridged peripheral channel connecting the outer ends of the radiating channels, upstanding outlet spuds on the sides of the ridges, secondary air passages adjacent ridge sides, and a Venturi bunsen discharging upwardly thru the bottom of the hub chamber toward said imperforate face.

7. In a gas burner of the character de-

scribed the combination of a Bunsen tube with shouldered inlet opening for the gas, an air shutter rotatably mounted on the shoulder, an inlet spud extending thru the shoulder, and guide means surrounding the spud and threaded into the shoulder, said guide means also acting to lock the spud and the air shutter in their proper positions.

8. A rose type gas burner having discharge orifices and secondary air passages cooperatively arranged so that each orifice will be flanked on at least one side with a secondary air passage, together with a Venturi bunsen delivering upwardly toward the burner face with substantially unimpeded discharge from the venturi in substantially the plane of the bottom of the burner.

9. A rose type gas burner having gas distributing channels with sloping top faces, outlet openings on the sloping faces, and secondary air passages, each outlet opening being arranged adjacent a secondary air passage, together with a Venturi bunsen delivering upwardly toward the burner face with substantially unimpeded discharge from the venturi in substantially the plane of the bottom of the burner.

In testimony whereof we have hereunto signed our names.

JOHN H. KOLTS.
